US0D1103364S

(12) **United States Design Patent** (10) **Patent No.:** **US D1,103,364 S**
(45) **Date of Patent:** **** Nov. 25, 2025**

(54) **NECK FAN**

- (71) Applicant: **SHENZHEN SHIWU TECHNOLOGY CO., LTD**,
Guangdong (CN)
- (72) Inventor: **Shaohua Zhong**, Guangdong (CN)
- (73) Assignee: **SHENZHEN SHIWU TECHNOLOGY CO., LTD**, Shenzhen (CN)
- (**) Term: **15 Years**
- (21) Appl. No.: **30/007,105**
- (22) Filed: **Jun. 6, 2025**

Related U.S. Application Data

- (63) Continuation-in-part of application No. 29/922,920, filed on Dec. 27, 2023, now Pat. No. Des. 1,095,808.

(57) **CLAIM**

The ornamental design for a neck fan as shown and described.

DESCRIPTION

FIG. 1 is a perspective view of a first embodiment of the neck fan showing my new design;
FIG. 2 is another perspective view thereof;
FIG. 3 is a front elevational view thereof;
FIG. 4 is a rear elevational view thereof;
FIG. 5 is a left side elevational view thereof;
FIG. 6 is a right side elevational view thereof;
FIG. 7 is a top plan view thereof;
FIG. 8 is a bottom plan view thereof;
FIG. 9 is a perspective view of a second embodiment of the neck fan;
FIG. 10 is another perspective view thereof;
FIG. 11 is a front elevational view thereof;
FIG. 12 is a rear elevational view thereof;
FIG. 13 is a left side elevational view thereof;
FIG. 14 is a right side elevational view thereof;
FIG. 15 is a top plan view thereof; and,
FIG. 16 is a bottom plan view thereof.
The broken lines in the drawings depict portions of the neck fan that form no part of the claimed design.

1 Claim, 16 Drawing Sheets
